(57) **CLAIM**

The ornamental design for a bicycle stem, as shown and described.

DESCRIPTION

FIG. 1 is a top plan view of a first embodiment of a bicycle stem showing our new design;

FIG. 2 is a bottom plan view of the first embodiment; FIG. 3 is a right side elevational view of the first embodiment;

FIG. 4 is a left side elevational view of the first embodiment; FIG. 5 is a front elevational view of the first embodiment; FIG. 6 is a rear elevational view of the first embodiment; FIG. 7 is a top plan view of a second embodiment of a bicycle stem showing our new design;

FIG. 8 is a bottom plan view of the second embodiment; FIG. 9 is a right side elevational view of the second embodiment;

FIG. 10 is a left side elevational view of the second embodiment; FIG. 11 is a front elevational view of the second embodiment; and,

FIG. 12 is a rear elevational view of the second embodiment.

1 Claim, 6 Drawing Sheets*FIG. 3.*

FIG. 4.

FIG. 6.

FIG. 5.

FIG. 7.

FIG. 8.

FIG. 9.

FIG. 10.

FIG. 12.

FIG. 11.
